UNITED STATES PATENT OFFICE.

JOHN M. CASE, OF COLUMBUS, OHIO, ASSIGNOR TO THE CASE MANUFACTURING COMPANY, OF SAME PLACE.

GRAIN-REDUCTION MACHINE.

SPECIFICATION forming part of Letters Patent No. 259,479, dated June 13, 1882.

Application filed February 11, 1882. (No model.)

To all whom it may concern:

Be it known that I, JOHN M. CASE, a citizen of the United States, residing at Columbus, in the county of Franklin and State of Ohio, have invented certain Improvements in 5 Grain-Reduction Machines, of which the following is a specification.

My machine is constructed with a pair of cracking or crushing rolls, to which a differential motion is imparted by a common belt passing around pulleys of different diameter on the roller-shafts, and around a third pulley on a shaft carrying an eccentric or pair of eccentrics employed to vibrate a feed-box, the 15 shaking movement of which maintains a more constant and uniform supply to the rolls than is practicable with the roller-feed commonly employed in connection with reducing-rolls. The belt also passes around a tightening-roll. 20 By thus using one common belt on the four pulleys I provide sufficient frictional resistance to adapt it to hold back on the slower of the two reducing-rolls and prevent the liability of slipping which occurs under the customary 25 mode of imparting a differential movement to reducing-rolls by the use of two belts driven by differential pulleys on one shaft.

In order that the invention and the manner of carrying it into effect may be fully understood, I will describe it in connection with the 30 accompanying drawings, in which—

Figure 1 is a perspective view of the machine. Fig. 1^a is a perspective view of the feed-box with adjacent parts. Fig. 2 is an elevation of the opposite side thereof on a larger scale. Fig. 3 is a section on the line 3 3, Fig. 2, of the belt-tightening device. Fig. 4 is a side elevation, partly in section, to illustrate the mode of adjusting the reducing-rolls for 35 grading the cracking or crushing. Fig. 5 is a central vertical transverse section.

A B are a pair of reducing hollow rolls, the former of which may run in fixed boxes in the frame C, while the roll B runs in boxes D D, 40 adjustable by means of set-screws E to regulate the grade of cracking or crushing.

The set-screws E are passed through hollow screws E', tapped into lugs c on the frame, and through lugs d on the boxes D, and receive 45 nuts F on their inner ends.

The roll B is held up to its work by springs

G, confined between the lugs d, and nuts H, adjustable on the hollow screws E' for regulating the pressure.

The springs G are made strong enough to 55 resist the pressure required for cracking the grain, but are adapted to yield and avoid injury to the machine in the event of a nail or small stone or other hard body falling between the rolls. In operation the springs G resist 60 the pressure required to crack or crush the grain, as the case may be, while the proximity of the rolls to regulate the grade is accurately adjusted by turning the set-screws themselves, for which purpose they are provided with 65 milled heads or hand-wheels e.

In order to impart a differential rotation to the rolls A and B, a driving-pulley, I, is keyed on the shaft of the roll A, and a driving-pulley, J, of larger diameter, on the shaft of the 70 roll B, and one common driving-belt, K, is passed around these pulleys and around a pulley, L, on a shaft, M, on which are also keyed eccentrics N N, carrying arms O O, which slide freely on rests R R, and carry a feed-box, P, 75 having a slide-regulator, p, as described in Letters Patent No. 239,029, dated March 22, 1881, heretofore granted to me, and provided with a suitable opening, Q, for introducing the grain. The vibratory movement imparted by 80 the eccentrics N delivers the grain over the serrated edge of the regulator p with great uniformity, and at the same time with such certainty that, on one hand, it is supplied equally to all parts along the length of the rolls, and, 85 on the other hand, any backing up of the grain, so as to choke the elevators commonly used to supply machines of this class, is impossible. The belt K is also passed around a tightening-pulley, S, which runs in a housing, T, having 90 a screw-shank, U, and a tightening-nut, u. The pulley-housing T is held to the frame by a clamp-bolt, V, placed in a slot, v, as shown in Fig. 3.

The relative velocity of the cracking-rolls is 95 perfectly governed by the size of the pulleys on their respective shafts. By the use of equal pulleys the rolls may be driven in unison at equal speed, which is desirable for some purposes.

The cracked grain is delivered through a chute, W, and discharged at w.

X represents a shutter covering a hand-hole, 25
2, to permit the operator to inspect the cracked
grain or chop as often as desired.

A suitable driving-pulley, to which the power
5 may be applied, is shown at Y.

It will be observed that my improved ma-
chine dispenses with the need of any separate
belting or gearing to operate the feed.

The operation of the feed by the same belt
10 which drives the cracking-rolls, and the fur-
ther frictional resistance applied to the same
belt by the tightening-pulley S, serve to hold
back on the roll B, so as to prevent it being
carried by friction with the driven roll A at
15 the same velocity.

My shaking feed-box insures a uniform sup-
ply of grain at all points along the length of
the cracking-rolls, and prevents the possibility
of grain backing up so as to choke the eleva-
20 tors, whereas with roller-feed devices in com-
mon use it is well known that choking fre-
quently results from an excessive supply, while
with an insufficient supply an undue propor-

tion of the grain will pass between the rolls
at the center or some other point. The shak-
ing feed is perfectly automatic, and dispenses
with the need of constant watching and fre-
quent adjustment, which are required with
feed-rolls.

Having thus described my invention, the fol- 30
lowing is what I claim as new therein and de-
sire to secure by Letters Patent:

1. The combination of rolls, pulleys thereon
of different diameters, a feeding device, and a
pulley operating said feeding device and an 35
endless belt common to all.

2. The combination, with the cracking or
crushing rolls A B, of the driving-pulleys I J
on their respective shafts, the feed driving-
pulley L, the tightening-pulley S, and a belt, 40
K, common to all.

JOHN M. CASE.
